(57) **CLAIM**

The ornamental design for a paint scraper handle, as shown and described.

DESCRIPTION

FIG. 1 is a front perspective view of the paint scraper handle of the present invention showing my new design;

FIG. 2 is another front perspective view of the paint scraper handle;

FIG. 3 is a front elevational view thereof;

FIG. 4 is a back elevational view thereof;

FIG. 5 is a right side elevational view thereof;

FIG. 6 is left side elevational view thereof;

FIG. 7 is a top plan view thereof; and,

FIG. 8 is a bottom plan view thereof.

The broken line showing on the drawing disclosure is for illustrative purposes only and forms no part of the claimed design.
